[57] ABSTRACT

A portable device is provided for determining the quality of man-made snow as represented by the amount of unfrozen moisture contained therein. The device embodies a flat plastic member adapted to be placed in contact with the surface of the snow and having two spaced electrical contacts exposed therein for engagement with the snow. An instrument such as a milliammeter is electrically connected to said contacts and calibrated to read in terms of the moisture content of the snow engaged by said member.

APPARATUS FOR MEASURING UNFROZEN MOISTURE IN SNOW

FIELD OF INVENTION

In the manufacture of snow for deposit on ski slopes, toboggan slides and elsewhere it is important to assure the desired quality of snow to present a suitable surface for use. Thus in applying snow to a slope for use in skiing it is desirable for at least the surface layer thereof to be in the form of substantially dry snow or "powder." However, the condition or quality of the snow produced by a snow making machine may vary widely depending upon the atmospherical conditions, the temperature, pressure and proportions of the air and water discharged from the gun or nozzle of the snow making machine and other variable factors. It is therefor practically impossible to establish and maintain uniform conditions of cooperation which will assure the production of snow which will have a predetermined quality as it settles on the ground or surface on which it is deposited.

As a practical matter and in the interest of economy, it is usual to supply the snow making gun with as much water as possible in order to produce as much snow as possible in a given length of time. On the other hand it has been determined that as little as 5 percent excess water in the mixture of water and air being discharged from a snow making gun may produce an icy patch of extended area whereas if as much as 30 percent excess water is used the whole area on which the snow is deposited may develop into "boiler plate," rendering it extremely hazardous or impossible to use in skiing.

In order to overcome this situation and assure the necessary control of the snow making equipment, frequent adjustments of the equipment are required. Nevertheless, it is necessary to wait until the snow produced has actually settle on a slope or trail and accumulated to a depth of a sixteenth of an inch or more before the actual character of the snow being produced can be determined. The method most generally used in testing the snow heretofore is to gather up a handful of snow and to squeeze it to see how it "packs." If the snow is too sticky or packy the amount of water being supplied to the snow making gun is reduced. If the snow is very dry the amount of water supplied may be increased to assure the production of the maximum amount of snow while maintaining a desired quality. However, such prior methods of testing are very erratic and call for considerable experience on the part of the person testing the snow. Furthermore, this manner of testing the snow produced does not enable the operator to know just how much more or less water should be supplied to the snow making equipment.

In order to overcome these difficulties and uncertainties in the operation of snow making machines the present invention provides a portable device which may be carried from place to place and applied to the snow to provide an accurate indication of the amount of unfrozen moisture contained in the snow at any point. The operator of the equipment then can make the necessary adjustments in the supply of water and air to any one or more guns in a system as needed to produce the desired quality of snow in any area. Moreover, the amount and nature of the adjustment required can be determined rapidly and with a much greater degree of accuracy than has been possible heretofore.

For this purpose the device of the present invention is provided with a sensing element presenting a flat surface formed of plastic or other electrical insulating material having spaced electrical contacts exposed therein. These contacts preferably extend throughout the major portion of the exposed surface of the sensing element whereby they will afford an accurate measurement of the amount of unfrozen moisture contained in the snow to which it is applied. A battery or other source of electricity is connected to the electrical contacts and an indicating instrument, such as a microammeter, is connected into a circuit including the battery and contacts to indicate the amount of current passing between the contacts and through the snow. The instrument may be calibrated to afford a direct indication of the amount of moisture in the snow whereby the snow making equipment may be quickly and accurately adjusted to increase or decrease the amount of water being supplied to the snow making equipment, if that should be necessary to produce the desired quality of snow.

Since the operation of snow making machines is frequently carried on at night, the instrument further may be provided with a light for the illumination thereof to facilitate reading thereof.

THE DRAWING

FIG. 1 is a perspective view illustrating a typical embodiment of the present invention;

FIG. 2 is a sectional view of the sensing element of the device illustrated in FIG. 1; and

FIG. 3 is a wiring diagram of a typical circuit which may be employed in the device of FIGS. 1 and 2.

PREFERRED EMBODIMENT

In that form of the invention chosen for purposes of illustration in the drawing the device is housed within a casing 2 which may be formed of plastic insulating material for the like and preferably is impervious to water and moisture. An instrument such as a microammeter 4 is enclosed within the casing and visible through a window 6 to permit direct and easy reading of the instrument. The dial 8 of the instrument is preferably calibrated and graduated to indicate the percentage of moisture in the snow to be tested. Further, since snow making operations are frequently carried on at night a light 10 is generally mounted in the casing 2 adjacent the dial 8 so as to illuminate the dial for easy reading of the instrument at all times.

A moisture sensing element 12 is connected to the instrument 4 by means of flexible conductors 14 which may be of any suitable length to permit the sensing element to be placed in contact with the snow to be tested and the instrument read conveniently by the person making the test or by a person controlling the operation of the snow making equipment. Thus, if desired, the instrument 4 may be located adjacent the gun used to produce the snow whereas the sensing element may be moved about from place to place in the area wherein snow is being deposited to test the quality of the snow at several points. In this way it is possible to assure accurate determination of the amount of unfrozen moisture present in the snow and the nature and amount of any adjustments in the water supply required to maintain the desired amount and quality of the snow being produced.

The sensing element 12 is preferably formed of electrically insulating material which is impervious to water and moisture. It is particularly desirable to form the body 16 of the sensing device of a material which is water repellent, such as "Teflon," so that it will rapidly shed any drops of water which may collect thereon and be capable of being wiped easily to keep the lower snow-contacting surface 18 of the sensing element dry.

The snow contacting surface 18 of the sensing element is preferably flat and has electrical contacts 20 and 22 exposed therein. These contacts as shown in FIG. 1 may consist of multiple strips 24 and 26 formed of metal and located closely adjacent to each other while being electrically insulated from each other by the material forming the body 16 of the sensing element. The strips 24 of the contact 20 extend in parallel spaced relation from a connector 28, whereas the strips 26 of the contact 22 are similarly attached or formed integral with a connector 30. One of the conductors 14, such as the line 32, is attached to the connection 28 while the other conductor 34 is attached to the connector 30.

The contacts or metal strips 24 and 26 are preferably embedded in the material forming the body 16 of the sensing element and are exposed in the snow contacting surface 18 of the body or may project a slight distance therefrom. The conductors or lines 32 and 34 may pass through a fitting 36 carried by the body 16 of the sensing element and provided with an O-ring 38 which is held in place and in sealing engagement with the fitting 36 by the plug 40.

When the snow-contacting surface 18 of the sensing element is placed in contact with the snow to be tested and the contacts 24 and 26 are connected into an electrical circuit, current will pass from contact 20 to contact 22 through the snow. The amount of such current will be proportional to the amount of the unfrozen moisture in the snow and will then serve to actuate the microammeter or instrument 4 to permit direct reading of the moisture content of the snow.

The placing of the metal strips 24 and 26 is preferably such that the strips are spaced one-sixteenth inch apart and will occupy a substantial area of the snow-contacting surface of the sensing element whereby the amount of current passing between the contacts will represent an average of the unfrozen moisture content of the snow engaged thereby and will not be unduly influenced by the presence of an individual drop of water which may be present in or on the snow being tested. Moreover by pressing the sensing element against the snow at several different points in a given area any deviations in the moisture contact of the snow can be averaged out to afford an extremely accurate measurement of the amount of unfrozen moisture therein. In actual practice, as little as 1 percent of excess moisture present in the snow being produced can be readily determined whereby the necessary adjustments in the snow making equipment may be made to assure the production of the maximum amount of snow of a desired quality at all times.

The electrical circuit employed for indicating the amount of unfrozen moisture in the snow may be varied considerably. However, one circuit arrangement which has been utilized effectively is shown in FIG. 3. As there indicated, current for actuating the device is supplied from a source 42, such as a mercury battery, one side of which is connected to the microammeter 4

through the conductor 44 which is connected to the contact 20 in sensing element 12 by conductor 32. The contact 22 is connected to the other side of the battery 42 through conductor 34, switch 46, variable resistor 48 and fixed resistor 50 in line 52. A normally open switch 54 is connected between the lines 32 and 52 to close a circuit through the ammeter for adjustment of the ammeter to full scale by means of variable resistor 48 prior to use of the testing device.

10 When the device is to be used to determine the amount of unfrozen moisture in the snow, the sensing device 12 is pressed against the surface of the snow as shown in FIG. 2 with the snow-contacting surface 18 and the exposed contacts 20 and 22 of the sensing device in firm engagement with the snow. Upon closing of the switch 46 current will be caused to flow through the snow from the strips 24 of contact 20 to the strips 26 of contact 22 so as to actuate the instrument 4. The amount of such current will depend upon the amount of unfrozen moisture in the snow and therefore the pointer or indicator 56 of the microammeter or instrument 4 will move over the dial 8 to indicate the amount or percent of unfrozen moisture in the snow. In this way the quality of the snow previously produced can be numerically evaluated and the need to increase or decrease the supply of water to the snow making equipment and the amount of any change required to produce snow of a desired quality can be instantly and directly determined.

15 20 25 30 35 Since the making and testing of snow is frequently carried on at night the device of the present invention may be provided with a light 10 energized by a battery 56 through lines 58 and 60. A switch 62 is included in line 58 to prepare the light circuit for use and the lighting circuit is closed upon operation of the double pole switch 46 when actuated in testing the snow. The light 10 then need only be utilized when necessary and when carrying out a snow testing operation.

30 35 40 45 The construction thus provided is easily portable so that it may be moved about from place to place to obtain several indications of the unfrozen moisture content of the snow. As a result, any error which might result from placement of the sensing element upon an isolated spot which is wet or contains an excessive amount of moisture can be eliminated by placing the sensing element on several other spots or areas representing usual average moisture containing snow. Further, by forming the body of the sensing element of "Teflon" on other material which tends to shed or repel moisture the snow-contacting surface of the sensing element can be readily wiped dry and the danger of carrying moisture from point to point on the sensing element itself is eliminated.

50 55 60 While the particular embodiment of the invention shown in the drawing and described above has proven very successful in use, the form, construction and circuitry employed therein are capable of numerous changes and modifications. In view thereof it should be understood that the invention as herein shown and described is intended to be illustrative only and is not intended to limit the scope of the following claims.

I claim:

1. A portable device for use in determining the quality of machine made snow comprising an element presenting a substantially flat surface adapted to be placed in contact with the snow to be tested, said element having a plurality of spaced electrical contacts exposed in

said surface and electrically insulated one from the other, a casing having an electrical instrument and a source of electrical current therein, flexible electrical conductors connected to the electrical contacts in said element and to the electrical instrument and source of current in said casing to permit said element to be moved about and placed in contact with the snow to be tested while the casing is carried in the hand or otherwise supported, said electrical instrument being responsive to the amount of unfrozen moisture contained in the snow against which the flat surface of said element is pressed and being calibrated to indicate the moisture content of the snow thus contacted by said element and electrical contacts.

2. A device as defined in claim 1 wherein said element has an exposed surface for contact with the snow which is formed of plastic material in which said elec-

trical contacts are embedded so as to be substantially flush with said surface.

3. A device as defined in claim 2 wherein said plastic material is "Teflon."

5 4. A device as defined in claim 1 wherein said contacts are in the form of a plurality of substantially parallel electrically conducting strips of material occupying the major portion of the snow-contacting surface of said element.

10 5. A device as defined in claim 1 wherein a battery is mounted in said device and a normally open switch is interposed between said instrument and contacts for manual closure to actuate said instrument.

15 6. A device as defined in claim 1 which includes a light for illuminating said instrument upon closure of said switch.
